CLAIM

The ornamental design for a display screen or portion thereof with graphical user interface associated with insulin delivery, as shown and described.

DESCRIPTION

FIG. 1 is a front view of a display screen or portion thereof with graphical user interface according to one embodiment of the design;

FIG. 2 is a front view of a display screen or portion thereof with graphical user interface according to another embodiment of the design;

FIG. 3 is a front view of a display screen or portion thereof with graphical user interface according to yet another embodiment of the design;

FIG. 4 is a front view of a display screen or portion thereof with graphical user interface according to yet another embodiment of the design; and,

FIG. 5 is a front view of a display screen or portion thereof with graphical user interface according to yet another embodiment of the design.

The broken lines showing the device, the display screen, and portions of the graphical user interface are included for the purpose of illustrating portions of the article and environmental subject matter and form no part of the claimed design.
